Inventor:

Charles H. Kenney,
By his Atty, T. H. Richards.

UNITED STATES PATENT OFFICE.

CHARLES H. KENNEY, OF NEW LONDON, CONNECTICUT, ASSIGNOR, BY MESNE ASSIGNMENTS, TO KENNEY ELECTRIC COMPANY, OF NEW LONDON, CONNECTICUT, A CORPORATION OF CONNECTICUT.

ELECTRIC RAZOR.

Application filed March 17, 1921. Serial No. 453,020.

To all whom it may concern:

Be it known that I, CHARLES H. KENNEY, a citizen of the United States, residing in New London, in the county of New London and State of Connecticut, have invented certain new and useful Improvements in Electric Razors, of which the following is a specification.

My present invention relates to electrical-
ly operated razors, and one object is to pro-
vide a safety razor, the blade of which is
electrically actuated for cutting purposes.

Another object is to provide a safety razor
in which the blade under normal conditions
is electrically actuated for cutting purposes,
but which is capable of use as an ordinary
safety razor, if means for supplying the
electric power is for any reason unavailable.

One feature of my invention is the use
of a single blade movable for cutting pur-
poses, which movement in the present em-
bodiment is oscillatory.

Another feature is the use of a single
blade movable for cutting purposes by elec-
trically actuated means.

Another feature is the use of a single
blade movable for cutting purposes by
means actuated by an electric solenoid.

Another feature is the use of a pivotally
movable cover for retaining the blade in
cutting position.

Another feature is the use of a pivotally
movable cover for retaining the blade in
cutting position and which also is a facial
guide, and a guard for the cutting edge
of the blade.

These and other objects, features and
capabilities of my invention will be dis-
closed in the course of the following de-
scription.

In the accompanying drawings which
show one embodiment of my invention, and
which form part of this specification,

Figure 1 is a longitudinal sectional view
of my razor.

Fig. 2 is a fragmentary detail view, on
the line 2—2 of Fig. 1, looking in the direc-
tion of the arrow of Fig. 1, partly in section,
and on an enlarged scale.

Fig. 3 is an exterior view of the portion
of the razor shown in Fig. 2; showing the
latch cover in raised position.

Fig. 4 is a plan view of the cutting mecha-
nism of the razor.

Fig. 5 is a plan view of the blade sup-
porting plate, and an edge view of the same
shown in projection below.

Fig. 6 is a detail side view, and an end
view in alined projection, of the support-
ing plate actuating crank; Figs. 3, 4, 5, 60
and 6 being on the scale of Fig. 2.

Similar reference characters or numerals
refer to similar parts throughout the several
views.

Referring to Fig. 2, my razor, which is
made of any suitable metal, or material,
comprises a support A, having a base 10
and body 11 extending transversely thereto.
The base 10 and body 11 are provided with
communicating interior chambers 12 and 13, 70
the chamber 12 being larger than the cham-
ber 13. The chamber 13 communicates with
a bore 14, in the body portion, shown in
outline, which bore is threaded, as at 15,
Fig. 1, for receiving the handle B later
described.

The base 10 is provided on its lower lon-
gitudinal edge with a series of guard prongs
16, and on the upper longitudinal edge with
an apertured flat lug or extension 17, Fig. 4, 80
located substantially midway of the upper
longitudinal edge. The ends of the upper
longitudinal edge are provided with a pair
of apertured extensions or ears 18, the pur-
pose of said lug and ears being later de- 85
scribed.

The razor supporting plate 19, is of rec-
tangular shape, and is provided on its upper
longitudinal edge, Fig. 5, with a flat lug or
extension 20, located substantially midway 90
of the upper longitudinal edge, and ar-
ranged for bearing upon the lug 17 of the
base 10, the supporting plate being pivotally
attached to the base 10, as by the transverse
pin 21 on the rear side of the flat lug or 95
extension 20 which engages in the apertured
flat lug 17 of the base 10.

The supporting plate 19 has on its front
surface spaced projections or studs 22 oval
or elliptical in shape in cross-section, the 100
oval or ellipses of the studs extending in
the longitudinal line of the plate, and has
on the rear surface of the plate a lug 23
which may be conveniently formed by slit-

ting, or partly cutting out, the plate 19 and turning rearwardly the slit or partly cut out portion to provide the lug, the purpose of the lug 23 being later stated.

- 5 The cover 24, has a rectangular body portion 25, when viewed as in Fig. 4, the upper longitudinal edge of which is provided at each end with a circular bearing 26 having a rounded extension 27, the circular bearing 10 26 being secured between the ears 18 of the base 10, as by the pins 28 passing through the bearings and ears, whereby pivotal movement of the cover is provided. The outer surface or face of the cover is curved, 15 downwardly, substantially as shown in Figs. 2 and 3 for passing as a guiding surface over the face of the user of the razor, the lower edge of the cover serving as a guard for the cutting edge of the razor blade. The cover 20 on its inner side is provided with bearing faces 29 and 30.

A spring, such as the flat spring 31, is secured to each end of the upper edge of the base 10, as by the screws 32, the springs 31 25 being provided with rounded portions 33 and outwardly extending ends 34, the intention being that the rounded extension 27 of the cover 24, shall engage in the rounded interiors of the rounded portions 33 of the 30 springs 31, for retaining the cover when it is in open position, and shall engage under the outwardly extending ends 34 for retaining the cover when it is in closed position.

The crank or bell-crank 35 comprises a 35 nose portion 36 and an arm 37, the nose portion having a recess therein for loosely receiving the lug 23 of the supporting plate 19, the crank 35 being pivoted in the chamber 13 of the body 11 of the support A, as 40 by the pin 38, and the arm 37 of the crank extending across the line of the bore 14 of the body 11, the arm 37 being held in this position by the spring 35' arranged between the nose portion 36 and the interior wall of 45 the chamber 13.

The handle B has an enlarged hollow portion 39, and a constricted portion 40 having a bore 41 communicating with the interior of the portion 39, which bore is intended to 50 receive a reciprocatable plunger, such as 42, one end of which is contactable with the arm 37 of the crank 35, for actuating the crank, the constricted portion 40 at one end being exteriorly threaded, or otherwise suitably 55 arranged, for securing the handle B to the body portion 11 of the support A.

The plunger 42 is reciprocatably actuated by electric means, in the present instance by a solenoid S, having a core attached to the 60 plunger and movable in one direction by electric current and, upon breaking of the circuit, movable in the reverse direction by spring means, the end of the plunger being contactable with the arm 37 of the crank 65 35, when the plunger is moved in one direc-

tion and out of contact therewith through movement in the reverse direction, whereby an intermittent movement is imparted to the arm 37, and movement of the supporting plate 19 afforded.

The razor blade 43, which is rectangular in form, may have a single cutting edge or two cutting edges, the blade shown being what is known as a Gillette blade, and is positionable on the front surface of the supporting plate 19, by means of circular spaced holes in the blade engageable over the studs 22 of the supporting plate 19, for cutting or oscillating movement of the blade with the supporting plate.

In operation. The parts described being assembled in operative relation, the cover 24 is swung open, as in Fig. 3, being held in position by engagement of the lugs 27 with the interiors of the curved portions 33 of the springs 31, and the razor blade is positioned on the supporting plate 19 as above stated. The cover 24 is then pushed downwardly, the faces 29 and 30 thereof bearing loosely on the razor blade to retain it on the supporting plate and yet not prevent cutting or oscillatory movement of the blade and plate, by engagement of the lugs or extensions 27 under the outwardly extending ends 34 of the springs 31. A suitable plug, 95 having a wire for connection to a source of electricity, is inserted in the end of the handle B, neither said plug, wire nor source of electricity being shown.

The current being turned on, the plunger 100 42 is thereupon reciprocally actuated, and moves the arm 37 of the crank 35, and causes movement of the supporting plate on its pivot pin 21, due to engagement of the nose 36 of the crank with the lug 23 of the supporting plate, whereby the cutting edge of the razor blade has a transverse movement of greater amplitude at the ends than at the middle of the blade, as shown in outline in Fig. 4.

Having thus described my invention, it should be understood that there may be modifications thereof and variations therein without departing from the spirit of the invention, or exceeding the scope of the appended claims.

What I claim and desire to protect by Letters Patent is:

1. In a device of the class described, the combination with a handle containing an electrically reciprocable plunger, of a blade support pivoted to said handle, a blade fixedly positioned on said support and means actuated by said plunger to impart an oscillatory movement to said blade support and the blade positioned thereon.

2. In a device of the class described, the combination with a handle containing electrically reciprocable means, of a blade pivotally attached to said handle, and means

actuated by said reciprocating means for imparting an oscillatory movement to said blade.

3. In a device of the class described, the combination with a handle containing reciprocating means, of a blade pivotally attached to said handle, and means actuated by said reciprocating means for imparting to the cutting edge of said blade, a transverse movement of greater amplitude at the ends than the middle, support and the blade positioned thereon.

4. In a device of the class described, the combination with a handle containing reciprocating means, of a blade support pivoted thereto, oval lugs on said support, a blade positioned on said support by means of said lugs, and means operable by the movement of said reciprocating means for imparting an oscillatory movement to said blade.

5. In a device of the class described, the combination with a handle containing reciprocating means, of a blade support pivoted to said handle, a blade positioned on said support and bell crank means operable by the movement of said reciprocating means for imparting an oscillatory motion to the blade, support and the blade positioned thereon.

6. In a device of the class described, the combination with a handle containing reciprocating means, of a blade pivoted to said

handle, and a bell crank lever pivoted in said handle, and actuated by the movement of said reciprocating means for imparting an oscillatory movement to the cutting edge of said blade.

7. In a device of the class described, the combination with a handle containing electrically reciprocating means, of a blade support pivotally mounted on said handle, a projection on said support and means cooperating with said lug and actuated by said reciprocating means for imparting an oscillatory movement to the blade support and the blade positioned on said support.

8. In a device of the class described, the combination with a handle containing electrically actuated plunger means, of a blade support pivoted on said handle, a blade positioned on said support, bell crank means pivoted to said handle, and actuated by said reciprocable means, for imparting an oscillatory movement to said blade support and the blade thereon as a unit, and tension means cooperating with said bell crank means to return the same into inoperative position at the end of each forward stroke of the plunger means.

CHARLES H. KENNEY.
